UNITED STATES PATENT OFFICE.

ELI E. DRYDEN, OF GRAND RAPIDS, MICHIGAN, ASSIGNOR TO PHILIP MATLER AND BENJAMIN F. BURK, COPARTNERS DOING BUSINESS UNDER THE NAME OF NATIONAL SWEEPER COMPANY, OF MARION, INDIANA.

DESIGN FOR A HANDLE AND CASING FOR CARPET-SWEEPERS.

SPECIFICATION forming part of Design No. 37,176, dated October 11, 1904.

Application filed August 8, 1904. Serial No. 220,023. Term of patent 7 years.

To all whom it may concern:

Be it known that I, ELI E. DRYDEN, a citizen of the United States, residing at Grand Rapids, in the county of Kent and State of Michigan, have invented a new, original, and ornamental Design for the Handle and Casing of Carpet-Sweepers, of which the following is a specification, reference being had to the accompanying drawings, forming part thereof.

Figure 1 is a plan view of the sweeper-case and handle. Fig. 2 is a side elevation of the

same, and Fig. 3 is an end elevation of the same.

What I claim as new, and desire to secure by Letters Patent, is—

The ornamental design for a carpet-sweeper casing and handle as shown.

ELI E. DRYDEN.
